M. MALLOVE, J. GREENBERG & P. KIEVES.
AUTOMATIC PIPE THREADING LUBRICATOR.
APPLICATION FILED DEC. 17, 1917.

1,265,692.

Patented May 7, 1918.

UNITED STATES PATENT OFFICE.

MORRIS MALLOVE, OF BROOKLYN, AND JACOB GREENBERG AND PHILIP KIEVES, OF NEW YORK, N. Y.

AUTOMATIC PIPE-THREADING LUBRICATOR.

1,263,692.

Specification of Letters Patent.

Patented May 7, 1918.

Application filed December 17, 1917. Serial No. 207,441.

To all whom it may concern:

Be it known that MORRIS MALLOVE, a citizen of the United States, resident of Brooklyn, county of Kings, and State of New York, and JACOB GREENBERG, a subject of the King of Roumania, resident of New York, county of New York, and State of New York, and PHILIP KIEVES, a citizen of the United States, resident of New York, county of New York, and State of New York, have invented certain new and useful Improvements in Automatic Pipe-Threading Lubricators, of which the following is a specification.

This invention relates to improvements in lubricators and particularly to types used in connection with pipe-cutting apparatus in which hand operated dies are caused to rotate about the end of the pipe to be threaded.

The principal object of the invention is to provide a device which may be attached to the die holder so as to rotate with the frame, the device carrying a quantity of liquid lubricant in such manner that the same is dispensed in controllable quantities as the device is rotated about the pipe.

A further object is to provide means whereby the lubricator is caused to operate in an effective manner, whether cutting right or left hand threads.

A further object is to provide means whereby the quantity of lubricant may be increased at will by operation of a hand pump combined with the apparatus.

These and other like objects are attained by the novel construction and combination of parts hereinafter described and shown in the accompanying drawing, forming a material part of this disclosure and in which:—

Figure 1 is a top plan view, of a lubricator the upper portion being removed.

Fig. 2 is a vertical sectional view of the same, taken on line 2—2 of Fig. 1.

Fig. 3 is a transverse sectional view, taken on line 3—3 of Fig. 2, and

Fig. 4 is a side elevational view, looking in another plane from that shown in Fig. 2.

In the drawings the numeral 10, indicates the pipe or tube being operated upon the dies or cutters 11, held in a ring 12, provided with operating handles 13, the same repre-

senting a conventional type of die stock. The invention comprises a hollow cylindrical casing 15, having a reduced lower end 16, below which extends a conical tube 18, having formed at its sides a pair of lugs 19, secured by screws 20, to the die stock 12. The casing 15 has an enlarged band 22, containing an internal screw-thread to which is fitted a hollow cover 23, having a raised corrugated ring 24, so that it may be conveniently turned to screw the cover into operative position on the casing 15. 55 60 65

Formed internally of the casing 15, is a flanged ring 26, upon which is secured a disk 27, the same acting as a fixed cover for the casing. Rising from opposite sides of the disk 27, which is held to the flange 26, by means of screws 28, are raised lugs 30, containing pivot screws 31, which are held in an adjusted position by means of lock nuts 32, the points 33 of the screws entering into the flat sides of a semi-spherical weight 34, so the same is free to swing thereon. 70 75

An off-set peripheral groove 35, is formed in the weight 34, and passing centrally therethrough, is an adjusting screw 37, the point of which is set in the groove 35, to 80 an adjustable depth, so as to bear upon the upper surface of a lever 38, pivoted in a bracket 39, fixed upon the disk 27, the free end of the lever extending transversely across the casing. 85

Mounted upon another bracket 40, fixed on the disk 27, is a lever 41, having a forked end 42, engaged with an oval plate 44, while the outer ends of the lever 41, has a turned end 45, extending below the lever 38, so that as the latter is raised or lowered, motion is transmitted to the fork 42. 90

A rod 47, is secured to the plate 44, the rod being substantially central with the casing 15, and extending down through a sleeve 48, 95 formed with the disk 27, through a packing 49, held in place by a packing ring 50, below which is a coiled compression spring 52, the lower end of which abuts against a collar 53, screw-threaded on the lower end of 100 the rod 47, which terminates in a conical head 55, adapted to control the opening through the tube 18.

It is to be understood that the casing 15, is adapted to hold a liquid lubricant which 105 flows out through the tube 18, when the

2
conical valve 55 is in a raised position, and the casing vertically above the work as indicated in Fig. 2, air entering through an opening 64 in the cover and passing through 5 an opening 56, controlled by a pin 57, rigidly set in the plate 44. In order to control the direction of movement of the weight 34, there is secured at one of its sides a gear 60, engageable with a pair of opposed springs 10 61 secured to the inner sides of the hand levers 62, pivoted in brackets 63, rising from the disk 27, so that by removing the cover 28, either of the springs 61 may be placed in operative position with respect to the 15 gear, while the other obviously will be moved outward so as to prevent contact.

If it be desired to increase the flow of the lubricant, an air pump 65 is used, the same being provided with an operating handle 66, extending upward through a knurled nut 20 67, secured to an off-set projection 68, of the casing 15, and having a communicating passage 69, so that as the knob or handle is operated, air is forced inwardly to the casing 15, pressing the lubricant downward in an obvious manner.

In operation, the casing 15, being secured to the die stock and the levers 62 moved into or out of contact with the gear, so that either a right or left hand thread may be cut, it 30 will be obvious that as the device is rotated upon an axis corresponding with the pipe 10, that the weight 34 moves from side to side so as to cause the screw 37 to act upon the lever 38, allowing it to raise and fall, 35 and through its connection operate the rod 47, opening or closing the opening through the conical tube 18.

From the foregoing it will be seen that a 40 readily controllable quantity of lubricant may be dispensed immediately adjacent to the dies, is controlled by operating the screw 37, and that the device will work equally well at cutting right or left hand threads.

45 As the disposition of the lubricant takes place only when the casing is in a vertical position, loss of lubricant is prevented, thereby providing an effective and economical device for the purpose.

50 Having thus described our invention what

we claim as new and desire to secure by Letters Patent, is:—

1. In a lubricator, the combination with the casing adapted to be rotated upon a horizontal axis, a central tubular stem formed with said casing, and a cover removably engaged therewith, of a valve adapted to control the passage in said tubular stem, a pivoted weight mounted in the upper portion of said casing, a lever operated by said weight, means for adjusting the action of 55 said lever, and means operated by said lever for controlling said valve.

2. In a pipe thread cutter lubricator, the combination with a hollow casing having an outlet closely adjacent to the pipe to be 60 cut, and a cover removably engaged with said casing, of a valve movable reciprocatively in said casing adapted to control the opening in said outlet, a disk fitted to the upper portion of said casing, lugs formed 70 with said disk, a weight pivoted in said lugs, a lever operated transversely in said casing, a screw in said weight contractible with said lever whereby its movement may be 75 adjusted, a second lever operated by the first named lever, connections between said second lever and said valve, means for the admission of air to said casing, means for controlling said air admission, and a hand operated pump in said casing whereby air 80 may be forced interiorly thereof.

3. In a pipe thread lubricator, the combination with a hollow tubular casing, having a conical outlet, and a cover suited to the upper portion of said casing, of a valve 85 movable in said casing adapted to control the passage through said outlet, a weighted semi-spherical pendulum pivoted in said casing, a lever contractible with said pendulum, connections between said lever and 90 said valve, and means in said casing permitting the semi-rotation of said pendulum in either of two directions.

In testimony whereof we have affixed our signatures.

MORRIS MALLOVE.
JACOB GREENBERG.
PHILIP KIEVES.
